UNITED STATES PATENT OFFICE.

ARTHUR H. SCOTT, OF OAK LANE, PENNSYLVANIA.

COMB.

1,117,257.

Specification of Letters Patent. Patented Nov. 17, 1914.

Application filed November 28, 1910. Serial No. 594,485.

To all whom it may concern:

Be it known that I, ARTHUR H. SCOTT, a citizen of the United States, and a resident of Oak Lane, county of Philadelphia, State of Pennsylvania, have invented an Improvement in Combs, of which the following is a specification.

My invention has reference to combs and consists of certain improvements fully set forth in the following specification and shown in the accompanying drawings, which form a part thereof.

The object of my invention is to provide an inexpensive and sanitary comb which may be employed in public lavatories for combing the hair and to avoid the necessity of having to use a comb which had been previously employed by other persons, as has heretofore been customary.

To accomplish the above objects, it is necessary that a comb shall be so cheaply made that it may be thrown away or destroyed after being used and consequently it is essential that the cost of manufacture of such a comb shall be reduced to a minimum.

While my object is, therefore, primarily to produce as an article of manufacture, a comb at an exceedingly low cost to be used as a sanitary article in public lavatories, the invention is nevertheless useful as providing a reasonably durable comb at a low cost for those who cannot afford the more expensive articles now upon the market.

I have found by experiment that a satisfactory comb may be produced from papier-mâché or other paper card of suitable thickness when properly blanked out and treated with varnish and densified.

In carrying out my invention, I employ suitable dies for stamping out a comb from a sheet of hard papier-mâché, card, or a paper card-board or any suitable formation having a dense structure which is coated with a varnish, preferably of shellac and alcohol with a coloring matter, preliminary to the action of the dies, the shellac coating thus provided, giving to the paper comb a fine outer gloss and an exceedingly smooth finish in all parts after densification by the dies.

In cases where the comb is required to have exceedingly fine teeth, I find it more convenient to secure this result by blanking out combs with the teeth wider apart and then securing two of such blanks together with the teeth in staggered relation. Where

desired, two thinner comb blanks may be secured together to produce the desired thickness, and if preferred, the said blanks may be subjected to the coating material preliminary to being united.

My invention comprehends, in addition to the above features, details of construction which will be better understood by reference to the drawings, in which:

Figure 1 is a plan view illustrating a comb blanked out of a sheet of paper board; Fig. 2 is a cross section of the same on line $z-z$; Fig. 3 is a cross section of the comb and dies; Fig. 4 is an enlarged cross section of a portion of the comb after leaving the dies; Fig. 5 is an end view illustrating the formation of the comb in two-ply; Fig. 6 is a cross section of a two-ply structure coated in a varnish or shellac composition; and Fig. 7 is an elevation of a portion of a two-ply comb illustrating the mode of securing closely arranged teeth therein.

2 is a strip or sheet of paper board or cardboard formed of papier-mâché or of superimposed and densified layers of paper having great tensile strength, and preferably such as is formed by the crossing of the fiber of paper in the several layers. This strip or sheet 2 is then placed between suitable dies and a blank in the shape of a tooth comb is cut therefrom, as more clearly indicated in Fig. 2. The blanked out portion 3 is of any thickness desired.

To give the comb a higher finish, it may be dipped in a quick drying varnish composed of alcohol and shellac, or instead of such a varnish, any other varnish may be employed which will provide a smooth surface which shall be hard when dry, and especially which shall be proof against moisture. The comb so varnished may be used in its varnished form, or preferably, it may be subjected to the action of burnishing dies, as indicated in Fig. 3, in which 5 represents the dies, 3 the blanked out comb of paper, and 4 the varnished or coating material. If this varnish is put on in a reasonably thin solution, such as by dipping the comb into it and then allowed to dry, the construction of the surface in the finished article will be as indicated in Fig. 4, in which the outer surface will be of highly polished construction resembling hard rubber and all edges will be highly finished. Furthermore, the extreme end of the teeth of the comb, as well as the lateral

edges thereof, will have the bevel shape indicated at 6 in Fig. 4 by the action of the dies, all of which will impart an excellent finish. By employing a shellac mixture for the varnish, colored with lamp black or other coloring matter to secure the proper color desired to the comb, it will not be necessary to subject the combs to the action of dies at the time that the shellac is placed upon the paper blanks, because the action of heat will soften the shellac finish and reform it at any time; and consequently in practice, the dipped comb blanks would be allowed to dry in quantity and subsequently be treated to the action of heat and pressure in the dies.

In place of using a single-ply paper board, a two-ply structure of comb may be employed with a finer grade of paper card, the two plies being indicated at 3, 3, and secured together by cement or varnish 7, as indicated in Fig. 5. These two plies may be secured together by shellac varnish in the finishing operation, if so desired, as indicated in Fig. 6. In this case, each of the plies 3 would be dipped in the shellac varnish and allowed to dry and subsequently two of these blanks thus coated with shellac would be superimposed and placed in the dies (Fig. 2) and subjected to heat and pressure which would cause the shellac of the two plies to adhere and at the same time give a finish to the comb on all sides.

When speaking of the application of heat and pressure to the shellac coated blanks, it is to be understood that, although it is preferable to heat the dies, the comb blanks coated with shellac may be warmed by being placed upon a steam table or other means for softening the shellac before the same is placed in the dies so that the heat of the dies need not be of a temperature sufficient to soften the shellac. This is the better practice, because the shellac, if softened first, may be permitted to set and harden with the finest kind of finish by the pressure action of the dies. In this way, the heat of the previously heated comb blanks will be sufficient to maintain the dies at as high a temperature as will be necessary. What I have stated with regard to the coating of the combs with shellac varnish to impart the finish to the combs, will be equally true by producing a solution of celluloid and coating the combs therein, the celluloid imparting to the surface of the paper a highly finished condition when subjected to pressure and heat.

Where fine tooth combs are required, it will be found more easy to produce the degree of fineness required by forming the

comb in two-ply, as above described. Such a construction is illustrated in Fig. 7, in which the upper ply 3 is provided with the teeth 8, whereas the lower ply 10 is provided with the teeth 9. When these two plies are secured together face to face, the teeth 8 and 9 become staggered or arranged alternately when looking at the side of the comb. It is evident that the two plies may be made with the same blanking dies and then one of them turned end for end so that the ends of the comb will come into proper alignment while producing the staggered effect of the teeth.

While I have shown my invention in the forms which are best adapted for the commercial use without involving excessive cost, I do not restrict myself to the minor details thereof, as these may be modified without departing from the spirit of the invention.

Having now described my invention what I claim as new and desire to secure by Letters Patent is:—

1. As an article of manufacture, a comb blanked out from a sheet of card-board and having the surface of the card-board impregnated with a varnish impervious to moisture and in which the outer surface of the comb and varnish is densified, the varnish coating at the outer surface completely shielding the paper, and on the under surface blending into pores of the paper to harden the same.

2. As an article of manufacture, a comb formed of two blanked plies of card-board each blank fully coated with a shellac composition and said coated blanked plies secured face to face by the adjacent shellac composition coatings and all of said coatings densified and smooth and completely shielding the card-board.

3. As an article of manufacture, a tooth comb consisting of two blanked plies of card-board of the same length, but in which the teeth are disposed in different relative positions as to length of the blanks, said blanks having their surfaces wholly covered by a shellac composition and permanently united together face to face by the said shellac composition and in which the teeth of the two plies are arranged in staggered relation and the outer surface of the shellac composition compressed to form a smooth polished structure.

In testimony of which invention, I hereunto set my hand.

ARTHUR H. SCOTT.
